E. A. GEOGHEGAN,
STEAM SUPERHEATER.
APPLICATION FILED DEC. 11, 1918.

1,367,691.

Patented Feb. 8, 1921.

Inventor:

Edward A. Geoghegan
By J. C. & H. M. Sturgeon
Atty.

UNITED STATES PATENT OFFICE.

EDWARD A. GEOGHEGAN, OF SAN FRANCISCO, CALIFORNIA, ASSIGNOR TO MILTON KRAMER AND EDWARD J. TALBOTT, TRUSTEES.

STEAM-SUPERHEATER.

1,367,691.

Specification of Letters Patent. Patented Feb. 8, 1921.

Application filed December 11, 1918. Serial No. 266,273.

To all whom it may concern:

Be it known that I, EDWARD A. GEOGHEGAN, a citizen of the United States, residing at San Francisco, in the county of San Francisco and State of California, have invented certain new and useful Improvements in Steam-Superheaters; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to improvements in steam superheaters, and particularly to such superheaters constructed and combined with modifications of the Foster type of marine boiler, and has for its object *inter alia* the construction of a superheater in such a manner and of such shape and contour that it can be installed between upper and lower banks of inclined water-tubes in such boilers. Another object of my invention is to 25 so modify the common type of Foster marine boiler that it shall comprise two banks of inclined water-tubes connected with common headers; said banks of tubes being spaced apart at such distance as will admit 30 the installation of my improved superheater between them in such a manner that the tubes of the superheater will be acted upon as effectively by the heat as are the boiler tubes.

35 These and other features of my invention are hereinafter fully set forth and explained and illustrated in the accompanying drawings in which:—

Figure 1, is a side view of boiler showing 40 an end view of my improved superheater installed therein, the side and base of the boiler setting being broken away.

Fig. 2, is a top or plan view of my improved steam superheater.

45 Fig. 3, is a view in elevation of one end thereof.

Fig. 4, is a view in elevation of the opposite end thereof.

50 Fig. 5, is a sectional detail showing a side view in elevation of the same installed in a boiler.

In these drawings, Fig. 1, A and A' indicate the front and rear headers; B and B' lower and upper banks of inclined water-tubes connecting said headers; C the steam-

drum; C' tubes connecting the steam-drum with the upper part of the rear header A'; C² tubes leading from the top of the front header A to the steam-drum C; D, D' and D² sections of the boiler setting, and D³ the smoke exit therefrom.

On the central part of the top of the lower bank of tubes B', I secure a baffle wall B² leaving passages around the ends thereof for the passage of the heat upward; and 65 under the upper bank of tubes B I secure baffle walls e and e' extending some distance inwardly from the front and rear headers A and A', leaving a passage for the heat to pass upward through the upper bank of 70 flues B; and on the central part of the top of the bank of flues B I secure a baffle plate F so as to leave heat passages f and f' past the ends thereof to the smoke exit D³.

In the space E between the upper and 75 lower banks of tubes B and B' upon suitable supports on the baffle plate B² I secure my improved superheater constructed substantially as follows:

At one end of the superheater I provide 80 headers G and G' each divided in the center by partitions g. From the upper of these headers G tubes g' extend to the lower headers G'. At the opposite end of the superheater I provide headers H and H'; the 85 upper of these headers H is provided with a central partition h and is provided at one end with an inlet I, and at the opposite end with an outlet I' to be connected up with the steam supply and output thereof in any 90 convenient manner (not shown). The upper headers G and H are connected by banks of tubes J and J' and the lower headers by lower banks of like tubes, so that the steam travels from the inlet portion of the header 95 H, through the tubes J to the header G at one side of the partition g therein, and thence through the tubes g' to the lower header G', and thence through the corresponding lower bank of tubes to the header 100 H' and thence longitudinally along the header H' and through the lower bank of tubes connecting it with the lower header G' at the opposite side of the partition g therein, and thence through the tubes g' to the 105 upper header G, and thence through the upper bank of tubes J' to the header H at outlet side of the partition h therein, thus completing a circuit through all of the headers and their connecting tubes, from the 110

inlet of the header H to the outlet thereof, thus continuously subjecting the steam in its passage thereto to the heat applied to the headers and tubes comprising it in its practical operation; and at the same time a compact and convenient installation thereof in a boiler of the type shown and described is most practically and effectively accomplished, as is necessary in the installation of 10 superheaters in marine boilers of the type shown and described.

Having thus shown and described my invention so as to enable others to utilize the same, what I claim as new, and desire to 15 secure by Letters Patent is:—

The combination of a steam boiler having banks of tubes spaced apart connecting the boiler headers, of a superheater mounted in

said space comprising substantially a pair of centrally divided headers connected by 20 short tubes, at one side of the boiler, a pair of headers at the opposite side of the boiler, one of which is centrally divided, and provides the inlet and outlet of the superheater, and the other a continuous header, and 25 banks of longitudinal tubes extending transversely to the banks of boiler tubes connecting the headers in such a manner that there is a continuous steam passage therethrough, and through the headers from the inlet to 30 the outlet thereof, substantially as set forth.

In testimony whereof I affix my signature.

EDWARD A. GEOGHEGAN.

Witnesses:

MILTON KRAEMER,
E. J. TALBOTT.
